(57) CLAIM

The ornamental design for bag for carrying, displaying, and serving beverages, as shown and described.

DESCRIPTION

FIG. 1 is a right, front, perspective view of a bag for carrying, displaying, and serving beverages showing my new design;

FIG. 2 is a top view thereof;

FIG. 3 is a front view thereof;

FIG. 4 is a bottom view thereof;

FIG. 5 is a left side view thereof, with the right side view being a mirror image thereof; and,

FIG. 6 is a rear view thereof; and,

FIG. 7 is a front, right, perspective view of an alternative embodiment of a bag for carrying, displaying, and serving beverages with the only difference being the omission of the label and the indicia on the surface of the bag.

The broken line showing of the bottle is included for the purpose of illustrating use and forms no part of the claimed design.
